Primary Examiner — Susan Bennett Hattan*Assistant Examiner* — Suzanne E Tisdell(74) *Attorney, Agent, or Firm* — Alix, Yale & Ristas,
LLP(57) **CLAIM**

The ornamental design for the heater for table use, as shown and described.

DESCRIPTION

FIG. 1 is a perspective view of a heater for table use; FIG. 2 is a front view thereof, the rear view being identical; FIG. 3 is a top plan view thereof; and, FIG. 4 is a left side view thereof, the right side view being identical.

The portions of the heater for table use shown in broken lines form no part of the claim.

1 Claim, 4 Drawing Sheets(56)
